J. J. NEUMANN

MOUTHPIECE FOR SAXOPHONES

Filed Aug. 10, 1923

UNITED STATES PATENT OFFICE.

JULIUS J. NEUMANN, OF CHICAGO, ILLINOIS.

MOUTHPIECE FOR SAXOPHONES.

Application filed August 10, 1923. Serial No. 656,681.

To all whom it may concern:

Be it known that I, JULIUS J. NEUMANN, a citizen of the United States, and a resident of Chicago, county of Cook, and State of Illinois, have invented certain new and useful Improvements in Mouthpieces for Saxophones; and I do hereby declare that the following is a full, clear, and exact description thereof, reference being had to the accompanying drawings and to the letters of reference marked thereon, which form a part of this specification.

This invention relates to improvements in mouthpieces for saxophones, clarionets and like musical instruments and consists of the matters hereinafter described and more particularly pointed out in the appended claims.

One of the objects of the present invention is to provide a simple and improved means for positively holding the reed in position upon its base, in such a manner as to eliminate the warping of the reed.

Another object of the invention is to provide an improved reed holder which will permit of a ready removal, replacement and adjustment of the reed.

A further object of the invention is to provide a protector for the reed, which is so mounted on the mouthpiece, that said protector may be quickly moved from a position covering the reed, to a position uncovering the same for playing, without removing the protector from the mouthpiece.

These objects of the invention, as well as the many advantages thereof will more fully appear as I proceed with my specification.

In the drawings:

Fig. 1 is a view in side elevation of the mouthpiece of a saxophone, clarinet, or the like instrument embodying my invention.

Fig. 2 is a bottom plan view of the same, with some of the parts shown in cross section.

Fig. 3 is a longitudinal vertical sectional view through the mouthpiece on an enlarged scale.

Figs. 4 and 5 are cross sectional views through the mouthpiece as taken on the lines 4-4 and 5-5 respectively of Fig. 3.

Fig. 6 is a perspective view of a housing member and reed clamping plate carried thereby, embodied in my invention, as the

same appears when removed from the mouthpiece.

Fig. 7 is a perspective view of a reed protector as the same appears when removed from the mouthpiece.

Referring now to that embodiment of the invention illustrated in the drawings:—10 indicates the mouthpiece body of a reed instrument, which is preferably made of cast metal, although it may be made of vulcanized rubber as is usual in instruments of this kind. 11 indicates that part of the mouthpiece body known as the "lay" surface which is formed to receive the reed 12. Said "lay" surface is made flat at the rear as at 13 to provide a base against which the reed is supported. 14 indicates the bevelled tip of the mouthpiece. In the bevelled part of the tip is provided a yielding pad 15 preferably of rubber, which provides a grip for the teeth and absorbs and relieves the reed vibration therefrom. Said pad is seated in recess, open at each side of the mouthpiece and provided by transversely extending, overhanging flanges 16. It is secured in place by shellac. (See Figures 1, 3 and 5.)

The bottom part of the mouthpiece is formed at each side of the rear flat end part 13 of the "lay" surface with longitudinal parallel faces 17 (see Fig. 4) which extend substantially at right angles to said "lay" surface. A longitudinal groove 18 is cut into the body of the mouthpiece along the top of each of said faces 17.

19 indicates a housing for the butt end of the reed. As shown in Fig. 6, said housing is made of sheet metal and is in the form of a channel having a transversely curved or arched bottom wall 20 and side walls 21, each of which terminates in an inturned flange 22. The flanged margins of the side walls 21 of the housing are normally sprung inwardly toward each other and when the housing is in position upon the mouthpiece body, the flanges 22 will engage in the grooves 18 and will exert a yielding pressure to fit tightly in position, with the arched bottom wall spaced a distance below the flattened end part 13 of the "lay" surface. The housing is locked to the mouthpiece by means of a set screw 23 which is threaded through an aperture in one of the side walls 21 to extend into a recess 24 in the associated shoulder 17 (see Figure 4). The housing 19

may be readily engaged upon or disengaged from the mouthpiece body 10 by sliding it thereon from the rear end of the "lay" surface,—the flanges 22 being first engaged within the grooves 18 on the mouthpiece. When thus applying the housing, its forward movement (towards the tip 14) will be limited by shoulders 10^a, 10^a at the forward ends of the grooves 18, said shoulders having a definite relation to the position of the recess 24, so that when the housing is arrested by engagement with the shoulders, the set screw is in line to engage the recess 24. Said aperture in said side wall 21 is arranged near the rear end of the housing and is formed by upsetting a part of said side wall to provide an outwardly extending, interiorly threaded boss 25. In line with said boss on the other side wall 21 is provided a similar boss 26. In both of the side walls 21, about midway between the ends of the housing, are provided outwardly extending lugs 27 which are also formed by depressing a part of said walls outwardly. The purpose of said lugs will appear later. 28 indicates an outwardly extending boss formed on the median line of the arched bottom wall 20 of the housing 19, midway between its ends. In said boss is anchored in any suitable manner, an interiorly threaded sleeve 29 to receive a clamp screw 30 (see Figure 3). That end of said screw within the housing has a swivelled connection with a clamping plate 31 and that end of said screw without the housing has a head 32, which is milled out as at 32^a (see Fig. 3) to provide an annular recess into which the outer end of the boss 28 may extend. In this manner the boss 28 may be made substantially deep to provide sufficient length of threads for the screw 30 without the necessity of having the head 32 thereof project too far outwardly from the housing. The clamp screw 30 as is apparent, does not engage the butt end of the reed directly but acts through the medium of the clamping plate which is formed to fit between the side walls of the housing and to engage the rounded butt end of the reed. When the screw 30 is loosened it will by reason of its swivelling connection with the clamping plate, dislodge and draw the clamping plate from its engagement with the reed and break any connection or adhesion between the reed and clamping plate due to moisture acquired in the playing of the instrument to which the mouthpiece is attached. The clamping plate is also rounded or arched transversely to fit the outer surface of the butt of the reed and will thus apply an even pressure which extends equally over the whole base against which the reed is seated. It is apparent from the foregoing that the reed may be removed and replaced with certainty and precision.

65 The reed which is usually made of bam-

boo, is easily injured, and this occurs most frequently when the instrument is not in use. A common practice is to slip a cap or hood of hard rubber over the tip end of the mouthpiece, which cap or hood is removed before playing and is thus oftentimes misplaced or broken. To overcome these disadvantages I provide a cap or hood which is so secured to the housing 19 that it may be moved from a position wherein it covers and protects the tip end of the reed against injury when the instrument is not in use (as shown in dotted lines in Figure 1 and in full lines in Figure 2), to a position where it uncovers the same for playing (as shown in full lines in Figure 1), the said cap or hood when in the second mentioned position, being entirely out of the way and in no manner preventing full freedom during said playing.

The improved protecting cap or hood comprises a channel shaped member 33 (see Fig. 8) which includes an arched bottom wall or web 34 and side walls or flanges 35, 35. At one end of the cap or hood, is an end wall 36 which connects the side walls together. At the other end of the cap or hood the side flanges 35 are extended beyond the arched bottom wall to form laterally spaced arms 37, 37, the free ends of which are offset inwardly toward each other. The free ends of said arms are provided with apertures 38, 38 as shown in Fig. 8, and said apertures are adapted to register with the threaded apertures formed in the bosses 25 and 26 in said housing side walls, said apertures being of such diameter as to receive said bosses. A screw 39 which is threaded into the boss 26 on one of the housing side walls, holds one of the arms 37 in place while the screw 23 before mentioned, which locks the housing 19, holds the other arm 37 in place. Upon the last mentioned arm about the aperture 38 is secured a washer 40 which is engaged by a part of the screw 23 in such a manner as to bind the same in any desired position. In one edge of said arms 37 are provided notches 41 which are spaced from the apertures 38 a distance equal to that between the bosses 26 and 27 on the housing side walls 21.

When the hood is in its normal reed protecting position, as when the instrument is not in use, the notches 41 in the arms of the protector engage the lugs 27 on the housing, the parts being locked together by tightening up the clamp screw 23. Under such conditions, the end wall 36 of the hood is spaced a short distance ahead of the tip of the reed (see Figure 2) and the arched bottom wall 34 is arranged in the plane of the similar wall of the housing 19 (see Figure 1). When it is desired to play the instrument, the clamp screw 23 is loosened and the hood is swung downwardly and rearwardly into the position shown in full lines

in Fig. 1 after which the clamp screw 23 is tightened to hold the hood in this position. It is apparent that the protector is not removed from the mouthpiece but is pivoted

thereto so that it may instantly be moved out of the way for playing, but it cannot be removed from the mouthpiece body with the usual displacement or breakage.

While in describing my invention I have referred to certain details of mechanical construction and arrangement of parts, I do not wish to be limited thereto except as may be pointed out in the appended claims.

I claim as my invention:

15. 1. The combination with the mouthpiece body of a musical instrument having a flat lay surface for a reed and having longitudinally parallel faces at each side of said lay surface, a housing to receive the butt end of said reed, said housing having side walls adapted for engagement with said faces, means for securing said housing directly to the mouthpiece with its side walls against said faces, a clamping plate in said housing for engaging said butt end of the reed to hold it against the lay surface, and means extending through the bottom wall of said housing for operating said clamping plate.

30. 2. In combination with the mouthpiece body of a musical instrument having a lay surface for a reed, a housing on said body to receive the butt end of said reed, said housing including a thin sheet metal bottom wall having a radially disposed, tubular projection, an interiorly threaded sleeve anchored in said projection, a clamping plate in said housing for engaging said butt end of the reed to hold it against the lay surface, and a screw engaged in said sleeve and having a swivelling connection at one end with said clamping plate and having a head on the other end without the housing.

35. 3. In combination with the mouthpiece body of a musical instrument having a lay surface for a reed, a housing on said body to receive the butt end of said reed, said body and housing having a coacting flange and groove engagement, a clamping plate in said housing for engaging said butt end of said reed to hold it against the lay surface, and a radially disposed clamping screw threaded through the housing and having a swivelling connection with said clamping plate.

50. 4. In combination with the mouthpiece body of a musical instrument having a lay surface for a reed, a housing on said body to receive the butt end of said reed, said body and housing having a coacting flange and groove engagement, a member carried by said housing and adapted to enter a recess in the mouthpiece body for locking said housing to said body, a clamping plate in said housing for engaging said butt end of said reed to hold it against the lay surface,

a radially disposed clamping screw threaded through the housing and having a swivelling connection with said clamping plate.

5. In combination with the mouthpiece body of a musical instrument having a lay surface for a reed, a housing on said body to receive the butt end of said reed, said housing having a transversely curved bottom wall and two substantially parallel side walls, each of which includes an inturned flange adapted to engage in grooves provided therefor in said body, a clamping plate in said housing for engaging said butt end of said reed to hold it against the lay surface, and a radially disposed clamping screw threaded through the housing and having a swivelling connection with the clamping plate.

6. In combination with the mouthpiece body of a musical instrument having a lay surface for a reed, a housing on said body to receive the butt end of said reed, said housing having a transversely curved bottom wall and two substantially parallel side walls, means in said housing for engaging said butt end of the reed to hold it against the lay surface, and a protector for the tip end of said reed including spaced arms, means providing a pivotal connection for said arms with the side walls of said housing whereby said protector hood may be swung from a position covering said tip end of the reed to a position uncovering the same for playing.

7. In combination with the mouthpiece body of a musical instrument having a lay surface for a reed, a housing on said body to receive the butt end of said reed, said housing having a transversely curved bottom wall and two substantially parallel side walls, means in said housing for engaging said butt end of the reed to hold it against the lay surface, and a protector for the tip end of said reed including spaced arms, screws providing a pivotal connection for said arms with the side walls of the housing whereby said protector hood may be swung from a position covering said tip end of the reed to a position uncovering the same for playing, one of said screws being capable of being actuated to lock the housing on said mouthpiece body and to lock said protector hood in either of its before mentioned positions.

8. The combination with the mouthpiece body of a musical instrument having a lay surface for a reed, a housing on said body to receive the butt end of said reed, said housing having a transversely curved bottom wall and two substantially parallel side walls, each of which has an outwardly extending lug, and a protector hood for the tip end of said reed including spaced arms, screws threaded into the housing side walls

and providing a pivotal engagement for said protector hood arms with said housing, so that said protector hood may be swung from a position covering said tip
5 end of the reed to a position uncovering the same for playing, said lugs on said housing side walls acting as stops for said arms to determine the position of said hood when covering said tip end of the reed.

In testimony that I claim the foregoing as 10 my invention, I affix my signature in the presence of two witnesses, this 6th day of August, A. D. 1923.

JULIUS J. NEUMANN.
